Primary Examiner—Caron D. Veynar

Assistant Examiner—Garth Rademaker

(57) **CLAIM**

The ornamental design for a geometric wall container, substantially, as shown and described.

DESCRIPTION

FIG. 1 is a front elevational view of a geometric wall container showing my new design;

FIG. 2 is a rear elevational view thereof;

FIG. 3 is a side elevational view thereof, the opposite side view being a mirror image thereof;

FIG. 4 is a top view thereof;

FIG. 5 is a bottom view thereof; and,

FIG. 6 is a cross-sectional view taken along line 6—6 of FIG. 3.
